UNITED STATES PATENT OFFICE

LOUIS LALANNE, OF MARSEILLE, FRANCE

DEVICE FOR ADJUSTING THE OPENINGS OF SCUTTLE PORTS AND THE POSITION OF THE PANE HOLDERS THEREOF

Application filed September 17, 1930, Serial No. 482,521, and in France November 15, 1929.

The present invention relates to a device for adjusting the openings of scuttle ports and the position of the pane holders thereof.

In the hitherto known constructions of scuttle ports it was only possible to effect one adjustment of the opening, the said adjustment being always either in a vertical or in a horizontal direction. The limitation of the adjustment in this manner is a drawback as in many cases it would be useful, for the purpose of directing the ventilation, to be able to adjust the opening in an inclined direction, i. e. to be able to put the pane holder of the port in an inclined position.

The present invention is intended to eliminate the said drawback and has for its principal object the provision of a device which renders it possible to incline the pane holder of a scuttle port at any desired angle of inclination, and which comprises in combination: a pane holder; means for moving said pane holder axially; means for rotating said pane holder; a single longitudinally movable member actuating according to its longitudinal position either said means for moving said pane holder axially or said means for rotating said pane holder; and means for locking said member either in the position for actuating said first-named means or in the position for actuating said second-named means.

By means of the device according to the invention it is rendered possible to construct an apparatus having a minimum of parts, which renders it possible to incline the pane holder of a scuttle port in any desired manner, i. e. at any desired angle, in order to direct the currents of ventilating air in the manner best suited to the requirements of the conditions of navigation existent for the time being.

A preferred constructional form according to the invention is illustrated by way of example on the accompanying drawings, in which:

Figs. 1, 2 and 3 show diagrammatically the mechanism for inclining the pane holder of a scuttle port according to the invention,

Fig. 4 is a partial cross section of a scuttle

port fitted with an adjusting device according to the invention in the closed position,

Fig. 5 is a similar section to that shown in Fig. 4, but shows the parts of the device in operative position,

Fig. 6 is a part elevation of the members for controlling the angle of inclination of the pane holder of the scuttle port,

Fig. 7 is an end elevation corresponding to Fig. 6, certain parts being shown in section, and

Fig. 8 shows in end elevation, partly in cross section, the device for effecting the axial movement of the pane holder which is known per se.

In the constructional form illustrated in the drawings the longitudinally movable member controlling the longitudinal displacement of the pane holder and likewise the angle of inclination of the latter comprises a manipulating member or hand wheel 2 which is longitudinally displaceable and is provided with a hub 3 having external grooves 4 adapted to be engaged by a locking pin 5. The said locking pin serves to determine the longitudinal displacement of the said manipulating member 2. The said hub 3 terminates in a hollow socket 6 which is preferably of rectangular cross section. The socket 6 is adapted to fit exactly over a square portion 7 carried by a toothed wheel 8 which turns upon a journal pivot 9 carried in the stationary frame 10 of the scuttle port.

The toothed wheel 8 actuates by means of teeth 11 a ring 12 carrying teeth 13 which form a toothed thread which is in engagement with a thread 18 of the ring of the pane holder. This ring by its rotation upon itself effects the opening of the scuttle port parallel to its closing joint and operates in known manner.

Parallel to the toothed wheel 8 a toothed wheel 14 carried by the hub 3 of the hand wheel 2 is arranged. This toothed wheel 14 is in constant engagement with a toothed segment 15 provided upon a ring 16. The latter ring is provided at certain points with projections 17 which take into the thread por-

tion 18 of the ring 19 in which the pane holder 21 turns upon pivots 20.

The device for adjusting the inclination of the pane holder consists substantially (as shown diagrammatically in Figs. 1, 2 and 3) in the connection of the ring 16 by means of the toothed segment 15 with the toothed wheel 14, which is arranged on the hub 3, of the hand wheel 2 and is rotated by the latter during the adjustment of the pane holder which is effected in the following manner:

The hand wheel being in the position shown in Fig. 4 when turned actuates the toothed wheel 8, which, by means of the teeth 11, causes the ring 12 to turn upon itself, which latter through the agency of the thread 13 causes the ring 19 carrying the pane holder to move longitudinally away from its joint 22. This manner of operation is known.

After this first operation has been completed the locking pin 5 is withdrawn from its groove and the hand wheel 2 is then drawn backwards in the direction of the arrow in Fig. 5 into the position shown in this last-named figure. During this movement the socket 6 leaves the square portion 7 of the toothed wheel 8 and the socket enters the hub of the wheel 14 which is provided with a recess to receive it. The locking pin 5 then enters the second groove of the hub of the hand wheel and the said hub is now connected to the wheel 14. In order to adjust the inclination of the ring 19 and the pane holder 21 as desired it is then only necessary to operate the hand wheel 2 so as to rotate the hub 3 and to transmit a rotary movement through the toothed wheel 14 and the teeth 15 to the ring 16, which latter ring by means of its projections 17 moves the ring 19, the pivots 20 and the pane holder 21 through any desired angle according to the inclination of the scuttle port opening which it is desired to obtain. The closing of the scuttle port is effected by the reverse operation, the socket is brought back into position over the square portion of the gear 8 and, when it is actuated, the ring 19 moves the pane holder 21 longitudinally against its joint 22.

It will be understood that the details of construction may be modified in various ways without departing from the scope of the invention.

The teeth 15 may be arranged over the whole circumference of the ring 16 so as to enable the pane holder to be adjusted to any desired position of inclination from 0° to 360°.

I claim:

1. A device for adjusting the openings of scuttle ports and the position of the pane holders thereof, comprising in combination: a pane holder; means for moving said pane holder axially; means for rotating said pane holder; a single longitudinally movable

member actuating according to its longitudinal position either said means for moving said pane holder axially or said means for rotating said pane holder; and means for locking said member either in the position for actuating said first-named means or in the position for actuating said second-named means, substantially as described.

2. A device for adjusting the openings of scuttle ports and the position of the pane holders thereof, comprising in combination: a pane holder; gears for displacing said pane holder axially; a longitudinally displaceable member for operating said gears; means for locking said member in operative position with regard to said gears; means for rotating said pane holder about its axis; means for displacing said member longitudinally so as to disengage it from said gears and engage it with said last-named means; and means for locking said member in position after displacement, substantially as described.

3. A device for adjusting the openings of scuttle ports and the position of the pane holders thereof, comprising in combination: a stationary frame; an axially displaceable and rotatable pane holder mounted in said frame; a longitudinally displaceable hand wheel actuating said pane holder so as either to displace it axially or to rotate it, according to the longitudinal position of said hand wheel; a hub on said hand wheel provided with two annular grooves; and a locking pin on said frame engaging with the grooves to lock the hand wheel in the position for displacing said pane holder axially and also after horizontal displacement of said hand wheel in the position for rotating it, substantially as described.

4. A device for adjusting the openings of scuttle ports and the position of the pane holders thereof, comprising in combination: a stationary frame; a pivoted axially displaceable rotatable pane holder mounted in said frame; gears for displacing said pane holder axially; means for rotating said pane holder about its axis; a single longitudinally displaceable manipulating member for actuating either said gears or said means according to its longitudinal position; a hub on said manipulating member; a hollow socket of rectangular cross section on said hub; a member of rectangular cross section on said gears engaging said socket when said manipulating member is in the position for actuating said gears; means for displacing said manipulating member longitudinally so as to disengage said socket from said rectangular member and engage it with said means for rotating said pane holder; and means for locking said manipulating member in either of its operative positions, substantially as described.

5. A device for adjusting the openings of scuttle ports and the position of the pane

holders thereof, comprising in combination: a stationary frame; a pivoted axially displaceable rotatable pane holder mounted in said frame; gears for displacing said pane holder axially; means for rotating said pane holder about its axis comprising an externally toothed ring, a pinion engaging said ring, and tenons on said ring engaging said gears; and a horizontally displaceable manipulating member controlling said gears and also said rotating means according to its longitudinal position, substantially as described.

Signed at Marseille, France, this 3rd day of September, 1930.
